WEATHER STRIP FOR WINDOWS

Frank Austin and Edward G. Austin,
Fanwood, N. J.

Application March 9, 1937, Serial No. 129,783

6 Claims. (Cl. 20—68)

This invention relates to weather-stripping for windows and has for one of its objects the provision of a metal weather-strip which will maintain a constant and uniform contact with the window sash at all times.

Another object of this invention is to provide a metal weather-strip which is particularly adapted for loosely fitted sash and will automatically adjust itself to variations in the difference between the width of the bottom and top of the sash.

Another object of this invention is to provide a weather-strip which will eliminate noise and rattle of the window sash during high winds; is quickly and easily installed, and which may be cheaply manufactured.

With the above and other objects in view, as will hereinafter appear, the invention comprises the devices, combinations, and arrangements of parts hereinafter set forth and illustrated in the accompanying drawing of a preferred embodiment of the invention, from which the several features of the invention and the advantages attained thereby will be readily understood by those skilled in the art.

Figure 1 is a perspective view of a portion of a window frame and double sliding sash showing our improved weather-strip applied thereto.

Figure 2 is a sectional view of a portion of a window frame and sliding sash with our improved weather-strip applied thereto, the view being taken through the upper sash, and the lower sash being shown in top plan.

Figure 3 is a section taken through the weather-strip.

Figure 4 is a perspective view of the weather-strip.

In the embodiment of this invention selected for illustration, our improved weather-strip comprises a metallic parting bead or casing A having a bottom wall 1 (Figure 3), a side wall 2, a top wall 3, and a depending wall 4. This casing is substantially C-shaped in cross-section and may be formed by a continuous process in indefinite lengths.

Located inside the casing are spaced tubes 5 which register with the holes 6 and 7 formed in the bottom and top walls 1 and 3. The metal around these holes is forced into the ends of the tubes to securely hold them in their correct position.

Received within the casing is a member B, of substantially S-shaped cross-section, the walls 8 and 9 of which, have sliding contact with the walls 2 and 4 of the casing. The wall 10 is aper-

tured to receive the tubes 5 and is slidable thereon. Coiled compression springs 11 surround the tubes 5 and each spring has one of its ends reacting against the wall 1 of the casing A and its other end against the wall 10 of the member B. It will be obvious from the above that the member B is slidable in the casing A and is held in position and guided in a right line movement therein by the contact between the walls 2 and 8 and the walls 4 and 9. It will also be obvious that the compression spring 11 constantly urges the wall 10 towards the wall 3.

Our improved weather-strip is applied to windows in the following manner; the usual longitudinal groove 14 is cut in the upper sash 14' and 15 the parting-bead is removed from the groove 15 in the board 16 of the frame and a length of the weather-strip equal to the height of the upper sash, is placed in the groove 15, in such a position that the tongue or flange 17 of the member B enters the groove 14 in the sash. A groove 18 is cut in the lower sash 19 and a length of weather-strip equal to the height of the lower sash is placed in the groove 15 in a position so that the flange 17 of the member B enters the groove 18. The weather-strip is held in position in the groove 15 by means of wood screws 20, and, of course, the weather-strip is applied to both sides of the sash.

From the above it will be understood that the wall 21 of the member B is at all times spring urged into contact with the edge of the window sash to prevent the passage of air therebetween and that the sash may "swell," due to the absorption of moisture, without effecting their relationship. It will also be understood that due to this arrangement, the sash is resiliently held at all times, thereby eliminating noise caused by the movement of the sash during high winds. Further, the sash engages and is held in position by the wall 4 of the casing A, the tongue 17 and the wall 21 of the member B; therefore the sashes do not come in contact with the window frame with the result that the sashes slide on smooth metal only. This feature permits clearance at the edges of the sash and when the window frames are painted the windows will not stick.

From the foregoing description considered in connection with the accompanying drawing, the construction and several advantages of our improved weather-strip will be clearly and fully understood. It is apparent that the weather-strip may be used for the casement type windows, and it will be understood that the form, construction and arrangement of the elements may

be varied. Therefore, the privilege is reserved of resorting to all such legitimate changes therein as may be fairly embodied within the spirit and scope of the appended claims.

Having thus set forth the nature of the invention, what we claim herein is:

1. A weather-strip comprising a casing having bottom, top and side walls, tubes connecting the top and bottom walls, a member carried by and 10 slidably engaging said side-walls, said member being formed with a weather-strip flange, and spring means for urging said member towards the top wall of said member.
2. In a window having a frame and a sash 15 slidable therein formed with a longitudinal groove, the combination of a metallic parting-bead of substantially C-shape in cross section secured in said frame, a substantially S-shaped metallic weather-strip having one portion movably supported in said parting-bead and another portion projecting into the groove in said sash, and means normally urging said weather-strip toward said sash.
3. A weather-strip comprising a metallic parting-bead of substantially C-shaped cross-section, a substantially S-shaped member carried by said parting-bead, and having one portion movable in said parting-bead and another portion which is adapted to engage a window sash, and spring 25 means for urging said member towards said sash.
4. In a window having a frame and a sash formed with a longitudinal groove, the combina- 30

tion of a metallic parting-bead of substantially C-shaped cross-section, a plurality of tubes carried by said parting-bead, a substantially S-shaped metallic weather-strip having one portion movably supported in said parting-bead and slideable along said tubes and another portion projecting into a groove in said sash, means normally urging said weather-strip into said groove, and means extending through said tubes for securing said parting-bead in place in said frame. 10

5. A weather-strip comprising a substantially rectangularly shaped hollow casing having top and side walls and adapted to be used as a parting-bead in a window frame, an S-shaped member 15 slidable in and extending from one side of said casing, said member having two of its limbs engaging the side walls of said casing, and resilient means for constantly urging said slideable member against one of the walls of said casing.

6. A weather-strip for windows comprising a 20 hollow casing adapted for use as a parting-bead and having side and top walls, one of said side walls being formed with an opening, a member 25 slidable in and having a portion extending laterally from the casing through said opening, said portion having a bent over edge which is adapted to enter a groove in a window sash, and spring means for urging said member towards the top wall of said casing.
